PNEUMATIC LOOM STOPPING MECHANISM

Richard G. Turner, Worcester, Mass., assignor to
Crompton & Knowles Loom Works, Worcester,
Mass., a corporation of Massachusetts

Application November 25, 1940, Serial No. 366,988

11 Claims. (Cl. 139—336)

This invention relates to loom stopping mechanisms and it is general object of the invention to provide a pneumatic brake connected to a moving part of the loom and operating at the time of loom stoppage to arrest the part and by it stop the loom.

In my prior Patent No. 2,199,353 there is shown a pneumatic pump operated by the lay for controlling the weft ends of reserve bobbins. While carrying on certain experiments with the mechanism shown in that patent I discovered that it is possible to stop the loom very quickly by closing the inlet port to the pump. It is an important object of my present invention to provide a pump operated by the lay and having an intake which can be closed by some part having a movement when the loom is to be stopped, such as the shipper handle, to provide a closed pneumatic system the pressure within which will be altered and have the effect of stopping the loom.

It is customary to set the stopping mechanism so that the lay will stop in its forward motion before reaching the fell of the cloth when there is a fault either in the weft of the running shuttle or the warp threads, and it is of course necessary to stop the loom on its forward beat when a misplaced shuttle operates the protecting mechanism. Under these conditions the lay is stopped during its advance and I accomplish this result by providing a valve to be closed so that forward motion of the lay will be arrested by compression of air in the closed system. When stopping the loom by hand, however, it is customary for weavers to throw the shipper handle immediately after picking on the backward stroke of the lay, and under these conditions my invention operates to arrest the lay by the creation of subatmospheric pressure within the closed system.

When the loom is stopped by the weft stop mechanism it is ordinarily necessary to move the lay backwardly a sufficient amount to open the shed so that the faulty pick can be removed. It has been customary heretofore, because of the construction of stopping and braking mechanism used prior to my invention, to move the lay manually, but I find that the compressed air within the closed system has the effect of moving the lay rearwardly without requiring manual operation on the part of the weaver.

In the customary braking mechanism the strain of stopping the lay is transmitted through the top shaft and crank connectors, and also the loom gearing. It is a further object of my invention to connect the lay directly to the air pump and stop the loom without subjecting the usual driving parts to strain.

A still further object of my invention is to effect immediate release of the brake as soon as the shipper handle starts toward running position, thereby avoiding any possibility of starting the loom while the brake is still on.

With these and other objects in view which will appear as the description proceeds, my invention resides in the combination and arrangement of parts hereinafter described.

In the accompanying drawings, wherein a convenient embodiment of my invention is set forth,

Fig. 1 is an end elevation of a loom built according to my present invention.

Fig. 2 is an enlarged vertical section through the pump.

Fig. 3 is an enlarged vertical section through the valve.

Fig. 4 indicates the manner in which the compressed air within the system acts to move the lay rearwardly after it has been arrested in its forward beat, and

Fig. 5 is a plan view of the valve looking in the direction of arrow 5, Fig. 3.

Figure 6 is an enlarged view of the drop-wire and electrode structure shown at the right of Figure 1.

Referring to the drawings I have shown a loom frame 10 having a lay L mounted on lay swords 11, one of which is shown in Fig. 1. The lay moves about a pivot 12 at the bottom of the loom and is driven back and forth by means of a connector 13 deriving its driving force from a driving crank shaft 14.

The loom has a shipper handle 15 fastened to the shipper rod 16 and having a lug 17 for cooperation with a shipper lever 18 pivoted as at 19. The lever has a notch 20 which is normally occupied by the lug 17 when the loom is running and the shipper handle 15 is forward or in the full line position shown in Fig. 1. A rod 23 extends rearwardly to loom operating mechanism not shown but well understood and is attached by means of a collar 24 to a tension spring 26 anchored to the loom frame at 25. The effect of spring 26 is to move the shipper lever rearwardly or to the right as viewed in Fig. 1 when the loom is to be stopped.

When the loom is at rest lug 17 is above the notch 20 and the lever 18 is moved rearwardly by the spring as already described and exerts sufficient force on the shipper handle to hold the latter in rear or the dotted line position of Fig. 1. An upstanding horn 28 on the shipper lever engages the lug 17 for this purpose.

My invention operates with any of the well-known means for stopping the loom automatically, and as set forth herein reliance is placed

on movement of the shipper handle from running to stopping position to close the pneumatic system already mentioned. For purposes of illustration I have shown but one automatic means for rocking the shipper handle, namely, an electric warp stop motion, but it is to be understood that this is but one of several mechanisms which can be used to effect movement of the shipper handle to stopping position.

A drop wire 30 normally held in raised position by a warp thread W has passing therethrough an electrode bar 31 having a grounded outside sheath 32 and an insulated electrode 33 normally out of contact with the drop wire. An electric wire 34 leads to a source of electric power, such as a transformer 35, and then extends to a solenoid 36 having a core 37. A regularly rocking actuator 38 ordinarily misses a force transmitter 39 controlled by the solenoid. The transmitter is pivoted to a lever 40 from which extends a rod 41 attached to the shipper handle as at 42. During normal loom operation when the warp is intact and the drop wire 30 is raised, the actuator 38 passes to one side of the transmitter 39. When the drop wire falls, however, current flows from one side of the transformer along wire 43 to sheath 32, through the fallen drop wire to electrode 33, along wire 44 to one side of the solenoid, and from the latter back to the transformer along wire 34. Thereupon the member 39 is raised into the path of the actuator and lever 40 is rocked to effect movement of the shipper handle from running to stopping position through the connector rod 41, usually as the lay is moving forwardly. The stopping mechanism is similar to that shown in prior patent to Payne No. 1,873,465 and of itself forms no part of my present invention, and is timed to rock the shipper handle from the full to the dotted line position of Fig. 1 as the lay is moving forwardly, or to the left, Fig. 1.

All of the parts thus far described are of known construction and operate in the usual manner, the lay L moving backwardly and forwardly or toward the right and left as viewed in Fig. 1, during loom operation. The shipper handle and the parts with which it cooperates are shown for illustrative purposes only and I do not wish to be limited to the details set forth, inasmuch as it is sufficient for the purposes of my present invention if there be a part in the loom, such as the shipper handle, which is moved from running to stopping position and is held in stopping position by some such element as the spring 26. As already stated, it is also sufficient for the purposes of my present invention if a form of stop motion operates to move the shipper handle from running to stopping position, preferably though not necessarily during the forward beat of the lay, and I do not wish to be limited in the use of my invention to an electric warp stop motion.

In carrying my present invention into effect I provide an upright lever 50 pivoted to the loom frame as at 51 and connected as at 52 to a forwardly extending rod 53 attached at 54 to the lay. Lever 50 is also pivoted as at 55 to a rod 56 connected as at 57, see Fig. 2, to a piston 58 which reciprocates in the pump cylinder 59. The pump is held in fixed position on a stand 60 secured as at 61 to the loom frame.

The forward end of the cylinder is closed by a head 65 from which extends a tube 66 having a bore 67 communicating with the interior of the pump. The tube is preferably secured to a

small brass pipe 68 which leads forwardly and has the front end thereof provided with a tube 69 which is embedded as at 70 into a soft rubber tube 71 having a relatively small bore 72 extending therethrough. The mass of rubber or tube 71 may be inclosed within a metallic sheath 75 which is held by a bracket 76 mounted on the loom frame as at 77. The forward end of the mass of rubber 70 is formed with a conical socket 80 into which the bore 72 opens.

The shipper handle 15 carries a small plug 85 from which rearwardly projects a conical valve 86 proportioned to enter the conical seat 80. While I have shown the valve 86 as mounted directly on the shipper handle, I do not wish necessarily to be limited to this construction since it is sufficient if the valve 86 moves with a part which has a movement from running to a stopping position when the loom is to be stopped.

During loom operation the shipper handle is forward with the plug out of the socket and the lay reciprocates in usual manner. By reason of rods 53 and 56 the piston 58 moves back and forth in the cylinder 59, the piston moving forwardly as the lay advances and moving rearwardly on the backward stroke of the lay. During forward motion of the piston air will be permitted to escape through the seat 80. Should the loom be stopped automatically as by operation of the electric warp stop motion, the shipper handle will be moved rearwardly to disconnect the loom from its driving motor and the valve 86 will enter the seat 80 to close the latter and establish a closed pneumatic system including the pipe 68 and the volume of air in the pump in front of the piston. Further advance of the lay will immediately compress the air in the pump the effect of which is to cause prompt loom stoppage.

As soon as the lay has come to rest the compressed air tends to expand and in doing so will move the piston and therefore lever 50 and rod 53 rearwardly to move the lay back. When weaving is to be resumed the shipper handle will be moved forwardly and the valve 86 will move out of the pocket 80.

If the weaver wishes to stop the loom manually the shipper handle will be moved from running to stopping position during backward motion of the lay as soon as picking has been completed, and under these conditions the valve will enter the pocket to close the pneumatic system as piston 58 is moving rearwardly, thus tending to create sub-atmospheric pressures within the system, and the lay will be stopped in much the same manner as it does when resisted by compressed air. If it should be desired to move the lay any considerable amount beyond the position to which it is moved by the effort of the closed pneumatic system to reach normal atmospheric pressures, the shipper handle can be moved slightly to open the system.

From the foregoing it will be seen that I have provided a simple pneumatically operating loom stopping system which can be effectively closed by movement of some part of the loom from running to stopping position. It will further be seen that the system operates whether the lay is moving forwardly to compress the air or moving rearwardly to rarefy it. Furthermore, the tendency of the air within the closed system to assume normal atmospheric conditions is used to move the lay in a reverse direction as soon as it has come to rest. This is particularly useful

when the lay is moving forwardly and a fault in either the weft or warp system is to be corrected. Also, the closed system can be relieved by a slight forward motion of the shipper handle before the latter has moved far enough to start the loom, hence the brake is always relieved before the driving mechanism is connected to the loom. It will also be noted that the strain of stopping the lay is transmitted through rod 53 and lever 50 to the pump piston without subjecting the crank shaft 14 to any strain.

Having thus described my invention it will be seen that changes and modifications may be made therein by those skilled in the art without departing from the spirit and scope of the invention and I do not wish to be limited to the details herein disclosed, but what I claim is:

1. In stopping mechanism for a loom having a part which has a regularly recurring motion during loom operation, said part being incorporated into the loom so that stoppage of said part causes loom stoppage, an air pump connected to and operated by said part during loom operation and tending to create abnormal atmospheric pressures, hollow means connected to the pump forming with the latter a normally open pneumatic system, a member movable from running to stopping position at any time during operation of the loom when the loom is to be stopped, and means operated by the member when the latter moves to stopping position to close said pneumatic system and cause the air pump to exert a stopping force on the loom.

2. In stopping mechanism for a loom having a reciprocating lay, an air pump connected to and operated by the lay throughout a reciprocation of the lay, hollow means communicating with the pump and constituting with the latter a normally open pneumatic system, a member to move from running to stopping position at any point in the lay reciprocation when the loom is to be stopped, and means controlled by said member when moving to stopping position to close the pneumatic system and cause the air pump to exert a stopping force on the lay.

3. In stopping mechanism for a loom having a reciprocating lay, an air pump including a cylinder, a piston to be reciprocated in the cylinder, connections between the lay and the piston to reciprocate the latter by a force derived from the lay as the lay reciprocates, a member to have a movement from running to stopping position at any point in the lay reciprocation when the loom is to be stopped, hollow means connected to the cylinder constituting a normally open pneumatic system, and means operated by the member when moving to stopping position to close said pneumatic system, movement of the piston within the cylinder when the system is closed altering the pneumatic pressure within the closed system the effect of which is to offer resistance to further movement of the lay.

4. In stopping mechanism for a loom having a reciprocating lay, an air pump including a cylinder, a piston to be reciprocated in the cylinder, connections between the lay and the piston to reciprocate the latter by a force derived from the lay as the lay reciprocates, a pipe connected to the cylinder and having a normally open orifice, a loom controlling handle movable from running to stopping position at any point in the lay reciprocation when the loom is to be stopped, and a closing element on the handle for the orifice to be moved into the latter when the shipper

handle moves to stopping position to prevent passage of air through the orifice and thereby create a closed pneumatic system including the pipe and the pump the effect of which is to resist motion of the lay.

5. In stopping mechanism for a loom having a reciprocating lay, an air pump including a cylinder, a piston to be reciprocated in the cylinder, connections between the lay and the piston to reciprocate the latter by a force derived from the lay as the lay reciprocates, hollow means presenting a normally open orifice pneumatically connected to the cylinder, a loom controlling handle movable from running to stopping position at any point in the lay reciprocation when the loom is to be stopped, a closing element on the handle to be moved into the orifice to close the latter when the handle moves to stopping position, thereby preventing passage of air through the orifice during forward motion of the lay and the lay when moving forwardly tending to compress the air within the cylinder and thereby have its motion arrested, the air within the cylinder acting while the handle is in stopping position to exert a rearward force on the lay through said connections tending to move the lay rearwardly due to the compressed air within the cylinder.

6. In stopping mechanism for a loom having a reciprocating lay, an air pump including a cylinder, a piston to be reciprocated in the cylinder, connections between the lay and the piston to reciprocate the latter within the cylinder by a force derived from the lay as the lay reciprocates, a member to have a movement from running to stopping position at any point in the lay reciprocation when the loom is to be stopped, hollow means pneumatically connected to the cylinder having a normally open orifice through which air may pass into and from the cylinder, said means and cylinder constituting a normally open pneumatic system, and means controlled by said member to close the orifice when the loom is to be stopped, thereby closing the pneumatic system and preventing passage of air into or out of the orifice, motion of the lay subsequent to closing the pneumatic system creating an abnormal air pressure within the closed system which acts through the piston in said connections to resist motion of the lay.

7. In stopping mechanism for a loom having a reciprocating lay, an air pump including a cylinder, a piston to be reciprocated in the cylinder, connections between the lay and the piston to reciprocate the latter by a force derived from the lay as the lay reciprocates, a member to have a movement from running to stopping position at any point in the lay reciprocation when the loom is to be stopped, hollow means pneumatically connected to the cylinder having a normally open orifice through which air may pass into and from the cylinder, said means and cylinder constituting a normally open pneumatic system, and means controlled by the member to close the orifice when the loom is to be stopped, thereby closing the pneumatic system and preventing passage of air into or out of the orifice, motion of the lay creating an abnormal air pressure within the closed system which acts through the piston and said connections to resist motion of the lay, the abnormal pressure acting when the lay is stopped to give said lay a reverse motion.

8. In stopping mechanism for a loom having a rotating driving shaft and a crank connector

operated thereby connected to and causing reciprocation of a lay as the shaft rotates, an air pump comprising a cylinder, a piston to be reciprocated relatively to and within the cylinder, connections between the piston and the lay to cause movement of the piston by a force derived from the lay as the lay reciprocates, hollow means connected to the interior of the pump and constituting with the latter a normally open pneumatic system, and means to close said pneumatic system at any point in the lay reciprocation when the loom is to be stopped, movement of the lay subsequent to closing of the system creating abnormal pressure conditions within the closed system tending to resist motion of the lay by a force transmitted from the latter through said connections between the piston and lay independently of the crank shaft and crank connector.

9. In stopping mechanism for a loom having a reciprocating lay, a shipper handle movable from running to stopping position at any point in the lay reciprocation when the loom is to be stopped, an air pump including a cylinder, a piston connected to the lay and caused by the latter to reciprocate in the cylinder as the lay reciprocates, hollow means communicating with the interior of the pump and constituting with the latter a normally open pneumatic system, and a valve moving with the shipper handle to close said system when the shipper handle moves to stopping position, movement of the lay subsequent to closure of the system creating abnormal air pressures within the system tending to resist motion of the lay, and the first part of move- 35

ment of the shipper handle from stopping toward running position moving said valve away from said pneumatic system to open the latter.

10. In stopping mechanism for a loom having a reciprocating lay, a shipper handle movable from running to stopping position at any point in the lay reciprocation when the loom is to be stopped, loom controlling mechanism connected to and movable by the shipper handle and including means to hold said shipper handle in stopping position, means constituting a normally open pneumatic system, force transmitting means connected to and operated by a force derived from the lay as the lay reciprocates to act upon said system and tend to alter the air pressure within said system, and means moving with the shipper handle to close said system when the shipper handle moves to stopping position, whereupon the closed pneumatic system acts through said force transmitting means to resist further motion of the lay.

11. In stopping mechanism for a loom having a reciprocating lay, means constituting a pneumatic system normally open when the loom is running, a member connected to and operated by a force derived from the lay throughout a reciprocation of the lay tending to alter the air pressures within the normally open system, and means to close the system at any point in the lay reciprocation when the loom is to be stopped and thereby cause said member to develop abnormal air pressures within said closed system tending to resist motion of the lay subsequent to closure of the system.

RICHARD G. TURNER.
